CLAIM

The ornamental design for a machine tool as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a machine tool showing our new design;

FIG. 2 is a rear perspective view of the machine tool of FIG. 1; and,

FIG. 3 is another rear perspective view of the machine tool of FIG. 1, showing a sliding panel in an open position to expose an interior of the machine tool.

The broken line showing of the logo “HAAS. Multigrind® Radical” in FIGS. 1 and 2 is for illustrative purposes only and forms no part of the claimed design. Multigrind® is a registered trademark of Adelbert Haas GmbH of Germany. Additionally, the broken line showing of the structures in FIGS. 1-3 is for illustrative purposes only and forms no part of the claimed design.
